UNITED STATES PATENT OFFICE

FRANCES ROCKEFELLER KING, OF NYACK, NEW YORK, ASSIGNOR TO SAFETY KING CORPORATION, OF NEW YORK, N. Y., A CORPORATION OF NEW YORK

BANDIT-PROOF WINDOW PROTECTOR

Application filed July 10, 1931. Serial No. 549,838.

The present invention relates to protective devices for windows or doors through which transactions in money, securities, jewelry and other valuables are handled. Such protective devices are particularly useful for windows of bank tellers' compartments.

The present invention comprises essentially a bandit-proof or bullet-resistant exchange plate for a window or opening through which transactions in valuables are carried on and has for its primary purpose to provide an improved form and construction for an article of this nature. The bullet-proof exchange plate forms an auxiliary shelf presented to the customer on the outside of the bank partition and to the teller or other official on the inside of the partition, the main surface of the exchange plate approximating the horizontal plane, but having gradually curved surfaces to prevent the insertion of a gun beneath the

grill or other protective wall covering the main part of the window and also serving as bullet-deflecting surfaces to prevent a bullet fired at the teller or other official by an intruder from reaching its intended victim. An important consideration attached to my improved bandit-proof exchange plate resides in the fact that its installation calls for no change in the usual business procedure as carried on in the past by bank tellers, cashiers

the above-identified application of Albert Baker, equipped with one form of my improved bandit-proof exchange plate.

Figure 2 is a horizontal section of the same on the line 2—2, of Figure 1 showing the 50 bandit-proof exchange plate in plan.

Figure 3 is a vertical section on the line 3—3, of Figure 2.

Figure 4 is a detached perspective view of the exchange plate. 55

Figure 5 is a transverse section of the same on the line 5—5, of Figure 4.

Figure 6 is a transverse section on the line 6—6, of Figure 4.

Figure 7 is a detached perspective view of another form of my improved exchange plate. 60

Figure 8 is a transverse section on the line 8—8, of Figure 7.

Figure 9 is a transverse section on the line 9—9, of Figure 7. 65

Figure 10 is a vertical section from front to rear of the exchange plate on the line 10—10, of Figure 7.

According to the embodiment of my invention shown on the drawings, a wall or partition 1 which is preferably constructed of bullet-proof material, is provided with a suitable opening to receive a metal frame 2 provided with flat bars 3 arranged in vertical parallel planes inclined to the wall or parti- 70

struction and arrangement of parts is substantially similar to that shown and described in the above-identified copending application of Baker, Serial No. 542,231.

5 Extending across the lower ends of the bars 3, according to the present embodiment of my invention, is a horizontal plate 6 which is preferably constructed of bullet-proof material. Said plate is provided with an elongated notch 7 in its lower edge and with the addition of the bullet-proof exchange plate to be presently described forms a suitable opening for the passage of money and other valuables between cashier and customer. As 10 shown in Figure 3, a triangular bracket 8 is secured to the wall or partition on the inner side thereof. Extending through the notch 7 and supported by the wall or partition and bracket 8, is an exchange plate of improved 15 form and construction. Referring more especially to Figures 2 and 4, it will be seen that this exchange plate comprises a central flat portion 9 extending between diagonally opposite corners of the exchange plate on opposite sides of the window grill, said flat portion 9 being widened intermediately of 20 said corners and merging inwardly with the upwardly-curved surface of a raised flange 10 extending inwardly from the wall or partition 1 and around the adjacent inner corner thereof. Said flange is reduced in depth along the innermost edge until it merges into the central flat portion 9 of the plate. Said flange 10 is provided at its forward end with 25 a triangular lug 10a whereby it may be secured to the wall or partition 1. As shown best in Figures 4 and 5, the exchange plate is provided with an increasing depth of metal toward its left forward corner 11, the upper 30 surface thereof being merged into the flat upper surface of the central flat portion 9 of the plate. Extending through the thickened metal along the side edge is a notch 11a in alinement with the forward face of the triangular lug 10a, the lower edge of the transverse plate 6 being seated therein. By referring more especially to Figure 2, it will be seen that if a cashier takes his stand at the 35 right-hand side of the counter or table 4, his right hand may be conveniently employed for receiving and passing out papers, money and the like over the flat-surfaced area which extends substantially diagonally and without interruption from the forward right-hand corner of the outwardly presented portion of the exchange plate to the inner lefthand corner of the inwardly presented portion of said exchange plate and thus in effect provides a smooth shelf for the normal transaction of business. Nevertheless, in the possible event that the cashier is confronted by a bandit at the window, the former is given ample protection by reason of the right-hand edge and right-hand inner corner of the inwardly presented portion of the exchange 40

plate being provided with a flange curved upwardly away from the flat surfaced area for upwardly deflecting a bullet which may be fired through the restricted opening below the lower edge of the cashier's grill. Furthermore, the front left corner of the forwardly presented portion of the exchange plate is inclined upwardly and outwardly from the flat-surfaced area so that a pistol can be inserted below the grill in the direction of the cashier only with a downward tilt and thus precludes the possibility of a bullet reaching the cashier through the restricted opening.

Referring now to the modified form of my improved exchange plate shown in Figures 7 to 10 inclusive, said modified form may comprise a central bottom portion 12 merging laterally and rearwardly into a raised flange 13, and a forwardly-presented shelf 14 which may be hollowed transversely as shown in Figure 8 by thickening the metal around the forward corners 15 and 16 of the plate. Said raised flange 13 is preferably constructed with a maximum depth around the rear edge of the plate to afford protection to a cashier standing directly behind the window opening. This form of my invention may be provided with lugs 17 for attaching the exchange plate to the inner side of the wall or partition 1 and may be employed with or without the inclined grill bars and mirror 5 provided the front wall and window are made bullet-proof. It will be understood from this description that by making the notch 7 or exchange opening of suitable size in relation to the thickness and arrangement of the thickened or raised corners 15 and 16 of the shelf 14, it becomes impossible to insert a pistol through the exchange opening or to arrange it in any position suitable for firing a shot at the cashier above the raised flange 13.

I claim:—

1. A bandit-proof exchange plate adapted to be disposed at the bottom of a restricted opening in a cashier's grill, said exchange plate comprising portions presented outwardly and inwardly from the grill, said plate being provided with a flat-surfaced area extending across both of said portions of the plate, said inwardly-presented portion being provided with a raised flange extending along one edge and around an inner corner thereof, the upper surface of said portion merging into said flat-surfaced area, a corner of the outwardly-presented portion of the plate being raised above said flat-surfaced area on the side of said restricted opening opposite to the edge along which said raised flange extends.

2. A bandit-proof exchange plate adapted to be disposed at the bottom of a restricted opening in a cashier's grill, said exchange plate comprising a relatively smaller portion presented outwardly from the grill and a relatively larger portion presented inwardly

from the grill, said plate being provided with a flat-surfaced area extending substantially diagonally across the plate from the right outer corner thereof to the left inner corner 5 thereof, said relatively larger portion being provided with a raised flange extending inwardly along its right-hand edge to a maximum depth at its inner right-hand corner and decreasing in depth along its innermost edge 10 and merging into said flat-surfaced area near its left-hand inner corner, the outer left-hand corner of the plate being raised and the upper surface of the plate being inclined away from said corner and merged into said 15 flat-surfaced area.

3. A bandit-proof exchange plate adapted to be arranged below a cashier's grill with portions presented outwardly and inwardly with respect to said cashier's grill, said exchange plate being provided with a flat-surfaced area extending inwardly from the outwardly presented portion beneath and past said cashier's grill, the inwardly presented portion of said exchange plate having its upper 20 surface curved upwardly away from said flat-surfaced area around one corner and along one side extending between that corner and said grill and the outwardly presented portion of said exchange plate being inclined 25 upwardly and outwardly from said flat-surfaced area around a corner thereof diagonally opposite to the first-mentioned corner of the inwardly presented portion to produce a downward tilt to a pistol presented inwardly 30 between the lower edge of said cashier's grill and said exchange plate toward said upwardly curved surface.

4. A bandit-proof exchange plate adapted to be arranged below and spaced from the 40 bottom edge of a cashier's grill with portions presented outwardly and inwardly therefrom, said exchange plate being provided with a substantially unbroken area extending inwardly from the outer edge of the outwardly presented portion and inclined upwardly 45 to the front and side edge of one corner of the outwardly presented portion of said exchange plate, the inwardly presented portion of said exchange plate having its upper surface curved upwardly around the corner 50 thereof which is diagonally opposite to the first-mentioned corner of the forwardly presented portion of said exchange plate and toward the side edge of said inwardly presented portion between the second-mentioned 55 corner and said cashier's grill.

5. A bandit-proof exchange plate adapted to be arranged below a cashier's grill with portions presented outwardly and inwardly 60 therefrom, said exchange plate being provided with a flat-surfaced area extending substantially diagonally from one corner of the outwardly presented portion to the diagonally opposite corner of the inwardly presented portion, the other corner of the inwardly 65

presented portion of said exchange plate having its upper surface curved upwardly away from said flat-surfaced area around one corner and along the side of said plate between that corner and said grill, the outwardly 70 presented portion of said exchange plate being inclined upwardly and outwardly from said flat-surfaced area around its other corner substantially diagonally opposite to the corner of said inwardly presented portion toward which the upper surface of said plate is upwardly curved. 75
